Attorney.

UNITED STATES PATENT OFFICE.

JAMES A. BROWN, OF CEDAR RAPIDS, IOWA, ASSIGNOR TO PERFECTION GAS ENGINE COMPANY, OF CEDAR RAPIDS, IOWA, A CORPORATION OF SOUTH DAKOTA.

INTERNAL-COMBUSTION ENGINE.

1,261,354.

Specification of Letters Patent.

Patented Apr. 2, 1918.

Application filed March 8, 1917. Serial No. 152,662.

To all whom it may concern:

Be it known that I, JAMES A. BROWN, a citizen of the United States of America, and a resident of Cedar Rapids, Linn county, Iowa, have invented certain new and useful Improvements in Internal-Combustion Engines, of which the following is a specification.

My invention relates to improvements in internal combustion engines, and the object of my improvement is to automatically actuate the exhaust-valve of such an engine by utilizing part of the pressure of the resultant gases of combustion therein.

This object I have accomplished by the means which are hereinafter described and claimed, and which are illustrated in the accompanying drawings, in which Figure 1 is a side elevation of my improved internal combustion engine with parts broken away to thereby better disclose the internal construction; Fig. 2 is a sectional view, on an enlarged scale, of my engine, showing overlaid sections, one of the cylinder and the other of the auxiliary cylinder containing the exhaust-valve and its actuating piston; Fig. 3 is a horizontal section of part of said cylinder, and of said auxiliary cylinder as seen from below looking upwardly toward the under surface of the exhaust-valve; Fig. 4 is a diagrammatic view of said cylinders with their by-pass connecting conduit, the engine cylinder being shown in horizontal section, and Fig. 5 is a cross-section of the auxiliary cylinder.

Similar numerals of reference denote corresponding parts throughout the several views.

Fig. 1 is the representation of an internal combustion engine of the stationary horizontal type in which all the parts are of a well known construction, but equipped with my improved exhaust-valve actuating means. The engine cylinder 13 contains the usual reciprocating piston 10 and has in its combustion chamber or in communication therewith, a suitable inlet-valve and gas igniting means not shown.

The numeral 1 denotes an auxiliary vertically disposed cylinder mounted on the end of the engine cylinder 13 adjacent to the combustion chamber of the latter. This cylinder 1 is divided by means of the horizontal septa 18 and 5, of which the one contains a central valve seat for the exhaust-valve 7, while the other contains a

central bearing orifice for the upwardly extending stem of said valve, the latter passing into the chamber 19 in said cylinder.

Referring to Fig. 2, said chamber contains a piston 2 above the upper end of said valve stem, and in the head of the cylinder 1 is an inlet-port 14 placed in communication with an auxiliary exhaust-port 17 in the engine cylinder 13, by means of an exteriorly located by-pass conduit 9.

The numeral 4 denotes a horizontal arm secured to the upper part of the valve-stem 3 by means of a rivet 16, and a coiled compression-spring 6 is engaged between said arm and the partition 5 by being coiled about the stem 3 to ordinarily keep the exhaust-valve closed and to cause the stem 3 to lift the piston 2 to its uppermost position. The numeral 23 denotes an upwardly extending standard fixed on the partition 5 adjacent to said stem 3, and having lugs between which is pivoted an oscillating lever 15 which is provided with the notch or recess 20 adapted to receive the outer extremity of the arm 4 when the latter is lowered with the stem 3. The notch 20 is formed with an acute angle at its upper end to fit the like angular upper edge of the arm 4 and prevent the unseating of the latter when in said notch except under a certain condition hereinafter mentioned. The lower end of the lever 15 is beveled on its rear face to be spaced away from its supporting standard 23 to permit the lever to rock forwardly at certain times.

Another fixed standard 22 is positioned near the stem 3 and supports one end of a plate spring 21 whose free end bears against the arm 4 and yieldingly retains the latter in its seat in the notch 20 of said oscillatory lever 15.

The numeral 24 denotes a bell-crank lever, one end of which engages the beveled lower end of the lever 15 and is kept in contact therewith yieldingly by means of a spring 26 connected to its pivot stud and bearing against its other end. The cylinder 1 has a slot through which enters an inturned end of a lever 25 to bear against the free opposite end of the bell-crank lever 24. This lever 25 is operatively connected with the moving weights 29 of a speed-governor 28 actuated by the engine and shifting a flanged sleeve 27 on the crank-shaft 30, to cause the lever, an end of which is positioned between the flanges of said sleeve, when the

engine exceeds a determined limit of speed, to rock the said bell-crank lever to release the lower end of the oscillating lever 15, whereby the latter may rock freely, so that 5 the arm 4 cannot detach itself from it when the stem 3 is rocked by means to be described, thereby holding the exhaust-valve 7 open until the speed of the engine becomes reduced. This governing mechanism specifically, however, is claimed in an application for patent, Serial Number 153,439, 10 hence will not be further described herein.

The numeral 8 denotes a cylindrical pin fixed dependingly and eccentrically on the 15 lower surface of the exhaust-valve 7. Opposite said pin 8 in the head of the cylinder 13 is a large opening 12 through which may pass a tappet finger 11 fixed on the head of the engine piston 10.

20 When, as shown in Fig. 4, the engine piston 10 has receded far enough to uncover the auxiliary exhaust-port 17, the gases resulting from combustion pass through the conduit 9 and inlet-port 14 into the auxiliary chamber 19 and by their pressure, push down the piston 2, the latter likewise pushing down the valve-stem 3 and opening the exhaust-valve 7 away from its seat. The arm 4 on said stem passes downwardly along 25 the lever 15 and is caused by the reaction of the spring 6 to seat itself in and engage the notch or recess 20 under the hooked detent in said lever 15 to retain said valve in its open position, when the latter is held 30 fixedly by the engagement therewith of said bell-crank lever 24, and by the pressure of said spring 21. When the engine piston 10 returns toward the cylinder-head, its tappet pin 11 passes through the opening 12, en- 35 gaging the eccentric stud or pin 8 on the exhaust-valve, pushing it around a short distance to rock said valve and its stem in one direction, which pulls the arm 4 out of engagement with the recess 20 on the stand- 40 ard 15, rocking it and permitting the spring 6 to react and carry said stem and the overlying piston 2 upwardly to their first positions while closing the exhaust-valve.

It will be seen that the pressure of the 45 exhaust gases alone, after leaving the engine combustion chamber, is drawn upon to actuate my improved mechanism for opening the exhaust-valve, without taking any part of the working power of the engine, 50 which results in a considerable saving of power.

Since a large exhaust-port can be used with my engine, the combustion-chamber is quickly scavenged of the waste gases of combustion, which prevents overheating, and 55 also a saving of power because all such gases are exhausted and none are left to be compressed on the return stroke of the piston,

which causes a braking effect thereon. The effective horsepower of the engine is, by reason of all these savings, greatly increased.

It will be seen, also, that my device opens the exhaust-valve in proper time and duration to the different cycle movements of the engine and performs this duty automatically and independently of any special mechanical actuating devices, such as gears, cams, push-rods or levers, commonly employed for the purpose on four-cycle engines.

Having described my invention, what I claim as new, and desire to secure by Letters Patent, is:

1. In an internal-combustion engine, the combination with the exhaust-valve stem thereof, and the engine-piston, of valve locking means for said stem, means controlled by exhaust-gases of the engine for shifting said exhaust-valve open and locking its stem with said locking-device detachably, releasing-means actuated by the engine-piston for releasing said stem from said locking device, and mechanism also actuated by said piston to variably act in regulating the action of said releasing-means.

2. In an internal-combustion engine, in combination with the cylinder, the piston therein, said cylinder having an auxiliary exhaust-port leading from its combustion-chamber, an auxiliary cylinder having partitions dividing it into two chambers, one of said chambers containing a piston and being in communication above said piston with said auxiliary exhaust-port, the other chamber having an outlet-opening, the lowermost partition having an exhaust-port in communication with the combustion-chamber, an exhaust-valve seated movably in said port, the other partition being orificed, and the exhaust-valve having a stem provided with engaging-means passing through said orifice into the first-mentioned chamber into juxtaposition to the piston therein, locking-means in said first-mentioned chamber adapted to interlock with the engaging-means on said stem detachably, yieldable resilient means connected to said stem adapted to exert upward stress thereon and other resilient means engaged with and adapted to hold it interlocked with said locking-means yielding, said exhaust-valve having engaging-means on its lower face, and engaging-means on the adjacent part of the engine piston adapted to engage said valve, engaging means detachably to rock said exhaust-valve, releasing it from said locking-means when the engine-piston is nearing one limit of its travel.

Signed at Cedar Rapids, Iowa, this 2nd day of March, 1917.

JAMES A. BROWN.
